UNITED STATES PATENT OFFICE

TAGE GEORG NYBORG, OF MECO WORKS, WORCESTER, ENGLAND, ASSIGNOR OF ONE-HALF TO MARK FREDERICK HIGGINS, OF WORCESTER, ENGLAND

CONVEYER

Application filed March 6, 1930, Serial No. 433,758, and in Great Britain April 4, 1929.

The usual method of supporting the different sections of the troughing of a jigger conveyor employing shifting rollers has the disadvantage that it is difficult to prevent the 5 coal lying on the floor from accumulating round the rollers and so preventing them from working satisfactorily. Further, it is difficult to prevent the rollers from grinding into dust the coal falling on to the roller 10 path.

Also, if rollers on a common spindle are used, a large amount of unnecessary friction is produced if the spindle of the rollers is not in an exact position relatively to the trough 15 or underframe, which requirement it is practically impossible to ensure below ground at the coal face.

The object of this invention is to provide in jigger conveyors a much lighter and 20 cheaper top and underframe which will be free from the above objections.

According to the invention the troughing is supported on pairs of rollers, of the type 25 provided with shafts running on tracks, axially aligned and separately mounted in such a manner that they cannot fall off the underframe, but may be moved about with the underframe as a complete unit. The rollers have a sufficient amount of clearance between 30 the tracks on which their shafts run to permit a large amount of "out of alignment" between the underframe and the trough.

The trough is mounted on a bearer or top frame which extends over both rollers and 35 has laterally extending wings projecting beyond the width of the underframe, and adapted to prevent coal or other material from falling on to the roller paths. It is further provided with forwardly and rearwardly extending stops to prevent the underframe moving out of position. Conveniently, the bearer may be constructed from 40 a steel plate or a pair of steel plates in which lateral extensions or side wings are bent downwardly, and the front and back stops on both sides of the bearer are formed by downward bends, the troughing resting on the plate through the intermediary of one or more packing strips which may be formed

integrally with supporting brackets for the walls of the troughing.

The means for preventing separation of the rollers from the bottom frame may comprise one or more flanged plates adapted to be bolted in position after the rollers are set up and having an end overhanging the axle 55 of the roller, but obviously any other suitable or convenient means may be employed.

The invention is illustrated in the accompanying drawings in which:

Figure 1 illustrates a side view, and

Figure 2 an end view.

Turning now to the drawings the underframe comprises a bed frame formed of two transversely arranged angle plates 1, 2, supporting longitudinally arranged angle plates 3, 4, the latter providing a track for one end 65 of the shaft 5 of each of the rollers 6. The inner track for the shaft 5 of the roller is formed by a second plate 7 extending between the plates 1, 2, the plates 7 being preferably bent upwardly, as illustrated at 8, after the roller has been set up in position to prevent its separation by axial movement inwardly.

The bearer or top frame is formed of a pair of steel plates 9, 10, having lateral extensions or side wings 9a, 10a, deflected downwardly and extending over the roller tracks so as to protect them from dust falling from 70 the conveyor. The plates 9, 10, are also bent downwardly at their ends as shown at 9b, 9c, Figure 1, to form arcuate shoulders adapted to co-operate with the rollers 6 to prevent 75 dislodgment of the underframe. The trough 11 is mounted on the bearer plates 9, 10, through the intermediary of transverse bars 12, one of which has its ends 13, 14, bent upwardly to provide supports for the sides of 80 the trough 11. Obviously the bearer frame could be constructed of a single shaped steel plate if desired, but the construction illustrated where it possesses the necessary rigidity makes for lightness. The clearance 85 permitted to the rollers 6 both as regards endwise movement and tilt in a horizontal plane is made fairly substantial to accommodate 90 a certain amount of "out of alignment" when setting up the underframe.

In the form shown it will be appreciated 100

that the rollers are finally prevented from accidental separation by the inner plates 8 on the one part and the downwardly extending flanges 9a, 10a on the other part.

5 The complete frame with the transverse bars 12 can be readily made and set up, and when once assembled as a complete unit requires no further dismantling in case the conveyer has to be taken down.

10 The construction is light and, as will be readily realized, provides sufficient strength for ordinary usage.

I claim:—

15 1. In a supporting underframe for a jigg-
ing or shaking conveyer, a pair of axially
aligned loose rollers having axial shafts,
tracks on which the shafts are supported and
the rollers held thereby free from a supporting
surface, and a top frame supported on
20 said rollers, said top frame having wings to
extend above and beyond the paths of said
rollers and cover said tracks.

25 2. In a supporting underframe for a jigg-
ing or shaking conveyer, a pair of axially
aligned loose rollers having axial shafts,
tracks on which the shafts are supported and
the rollers held thereby free from a supporting
surface, and a top frame supported on
30 said rollers, said top frame including a steel
plate extended laterally to cover the roller
paths and extended downwardly at the ends
to provide stops for the rollers.

35 3. In a supporting underframe for a jigg-
ing or shaking conveyer, two pairs of tracks,
a pair of axially aligned, separately mounted
rollers having shafts running on said tracks
to hold the rollers free of a supporting sur-
face, and a bearer or top frame resting on
40 said rollers including a pair of steel plates
extended laterally to protect the roller paths
against dust and bent downward fore and aft
to provide stops.

45 4. In a supporting underframe for a jigg-
ing or shaking conveyer, two pairs of tracks,
a pair of axially aligned, separately mounted
rollers having shafts running on said tracks
to hold the rollers free of a supporting sur-
face, and a bearer or top frame resting on
50 said rollers including a pair of steel plates
extended laterally to protect the roller paths
against dust and bent downward fore and aft
to provide stops, one of each of said tracks
comprising a plate with a bent up side to
prevent axial dislodgement of said rollers.

55 5. In a supporting underframe for a jigg-
ing or shaking conveyer, a pair of supporting
angle bars, a second pair of angle bars
transversely mounted thereon, a second pair
60 of transverse bars in spaced relation to said
first pair, said transverse bars forming pairs
of tracks, and axially aligned and separately
mounted rollers located between said tracks
and having shafts running thereon, said
65 shafts supporting the rollers free of a bear-
ing surface, a bearer frame having laterally

extending wings supported on said rollers,
said bearer frame supporting the conveyer
trough.

6. In a supporting underframe for a jigg-
ing or shaker conveyer, two pairs of tracks,
a pair of axially aligned, separately mounted
rollers having shafts running on said tracks
to hold the rollers free of bearing contact, a
70 bearer or top frame resting on said rollers,
transverse strips resting on said top frame to
support a trough, one of said strips having
brackets, said top frame having wings adapt-
ed to extend over and beyond the said tracks,
75 said wings having downwardly bent, lateral
portions, and means to prevent said rollers
from becoming detached.

In testimony whereof I affix my signature.
